COIL AND LEAF SPRING ARRANGEMENT
FOR RAILWAY TRUCKSClaude L. Orr, Columbus, Ohio, assignor to The
Buckeye Steel Castings Company, Columbus,
Ohio

Application January 4, 1939, Serial No. 249,308

13 Claims. (Cl. 105—197.1)

This invention relates to improvements in coil and leaf spring arrangements for railway car trucks.

The main object of this invention is to supply 5 a spring ensemble providing easy riding qualities with a nominal amount of spring travel.

Another object is to provide a spring arrangement including a leaf spring or springs positioned within a transverse bolster of a truck.

10 With the foregoing objects outlined and with other objects in view, the invention consists in the novel features hereinafter described in detail, illustrated in the accompanying drawings, and more particularly pointed out in the appended 15 claims.

In the drawings:

Fig. 1 is a vertical sectional view of a portion 20 of a truck side frame and transverse bolster with my improvements incorporated therein, the section being taken on the line 1—1 of Fig. 2.

Fig. 2 is a top plan view with portions of the side frame broken away to facilitate illustration.

Fig. 3 is an end elevation.

Referring to the drawings, 4 designates a side 25 frame member of a truck having a bolster opening 5 for the reception of one end of a transverse bolster 6. The spring seat 7 at the top of the tension member of the side frame supports a spring seat brake hanger bracket casting 8 which 30 supports a group of coil springs 9. The number and size of these springs is determined from the load to be supported, and may, therefore, vary. In this particular case, the load to be carried and the space available requires the use of two 35 large coils and two small coils.

The transverse bolster rests on top of the springs and carries the body load to the spring group. As sufficient space is not available between the bolster and the spring seat 7 for the 40 application of one or more leaf springs, I so form the bolster as to receive and house such springs. As illustrated, two leaf springs 10 are used, spaced equal distances from the longitudinal center line of the end of the transverse bolster. Of course, 45 the size and number of these springs is determined by the load to be carried and the space available.

The leaf springs operate within the end of the bolster and they are supported on the spring seat 50 casting 8 by means of a block 11 which is arranged in the group of coil springs and is provided at its upper end with posts or plungers 12 which extend through openings 13 in the bottom 55 of the transverse bolster. Upstanding lugs 14 provided on the spring seat casting serve to posi-

tion the bottom of the block. Obviously the coil springs and block might rest directly on the spring seat 7 if the casting 8 is omitted.

Arc-shaped bearing seats 15 and 16 are provided inside the transverse bolster and bear upon the ends of the leaf springs for applying the load to the latter. The seat 15 may be cast integral with the bolster while the seat 16 may be an integral part of a spring block 17 which is secured to the end of the bolster by any suitable means 10 such as a bolt 18. The side walls of the bolster are extended as shown at 18a and provided with holes to receive the bolt.

When the leaf springs are loaded, an upward 15 force at the left end bears against the seat 16 and is transferred to the bolster through the bolt and the extensions 18a. The horizontal portion 19 at the top of the spring block prevents its 20 rotating when subjected to transverse loads due to track curvature, body roll, etc., and also releases the bolt from carrying the vertical load.

The upper surface of the bottom of the bolster is recessed as shown at 20 to receive the bottom 25 portion of spring bands 21 thereby positioning the leaf springs inside the bolster.

To apply the leaf springs 10, the bolt 18 and block 17 are removed. This enables the outer 30 ends of the springs 10 to be raised an amount sufficient to engage the bottom of the spring bands 21 in the recess 20. The block and bolt are then replaced and all parts are secured in their proper position. The leaf springs may be removed in a like manner.

The use of a coil and leaf spring ensemble is 35 desirable because the friction introduced into the group by the leaf spring or springs tends to dampen out the harmonic oscillations set up in the coils at certain critical speeds. The travel of the coil and leaf springs is the same and equal 40 to the group as a whole. The use of the leaf spring does not therefore introduce excessive travel.

Heretofore, it has been proposed to arrange 45 a leaf spring consisting of short leaves, transversely in the end of the bolster, but they were not intended for main load carrying members, but only to assist the coils when they are deflected to a near solid condition by heavy blows. In contradistinction, I arrange the leaf springs 50 longitudinally of the transverse bolster and the parts are so combined that these springs constitute main load carrying members.

While I have disclosed what I deem to be a 55 preferred combination and arrangement of parts, I do not wish to be limited thereto as there might

obviously be changes made in the form, construction and arrangement of the constituent elements as well as their modus operandi without departing from the spirit of the invention as 5 comprehended within the scope of the appended claims.

What I claim and desire to secure by Letters Patent is:

1. In a railway car truck, a side frame member 10 having a bolster opening, a bolster having an end portion extending into said opening, coil springs supported by the side frame member and supporting the end of the bolster, a leaf spring supporting said bolster, said leaf spring being arranged within and longitudinally of said end portion of the bolster, means for transferring a load placed on the leaf spring to the side frame member, said bolster having a recess in the upper surface of its bottom, and a spring band 15 encircling the leaf spring and extending into said recess.

2. In a railway car truck, a side frame member having a bolster opening, a bolster having an end portion extending into said opening and provided with an opening in its bottom, coil springs supported by the side frame member and supporting the end of the bolster, a leaf spring supporting said bolster, said leaf spring being arranged within and longitudinally of said end portion of the bolster, means for transferring a load placed on the leaf spring to the side frame member, the last-mentioned means comprising a block having an upstanding post extending through the opening in the bottom of the bolster 30 and engaging the leaf spring.

3. In a railway car truck, a side frame member having a bolster opening, a bolster having an end portion extending into said opening and provided with openings in the bottom thereof, a group of coil springs resting on the side frame member at the bottom of the opening and supporting the end portion of the bolster, leaf springs arranged within the end portion of the bolster, positioned longitudinally thereof and arranged at 45 opposite sides of the longitudinal center thereof, and a block supported by the side frame member and having a plunger means extending through the openings in the bottom of the bolster and into engagement with one of said leaf springs.

4. In a railway car truck, a side frame member having a bolster opening, a bolster having an end portion extending into said opening and having openings in the bottom thereof, a group of coil springs arranged beneath the end portion of the bolster and supported by the side frame member, leaf springs arranged lengthwise of the end portion of the bolster and positioned within the same, and a block supported by the side frame member, arranged between the coil springs and having plungers extending through the openings in the bottom of the bolster and into engagement with the medial portion of the leaf springs, said end portion of the bolster resting on the 60 end portions of the leaf springs.

5. In a railway car truck, a side frame member having a bolster opening with a tension member at the bottom thereof, a bolster having an end portion extending into said opening, spring 70 means supported by the top of said tension member and supporting said bolster, a leaf spring having substantially horizontally disposed leaves positioned within the bolster and arranged longitudinally thereof, and means supported by the 75 side frame member and cooperating with the

medial portion of the leaf spring, whereby the latter forms a main load carrying member.

6. In a railway truck, a side frame member having a bolster opening with a tension member at the bottom thereof, a bolster having a 5 box-shaped end portion extending into said opening, coil springs supported by the top of said tension member and on which the end of the bolster rests, a leaf spring having substantially horizontally disposed leaves arranged entirely 10 within the bolster and lengthwise thereof, said bolster having an opening in the bottom thereof, and means supported by the tension member of the side frame member, extending through the opening in the bottom of the bolster and co-operating with the medial portion of the leaf spring whereby the latter forms a main load-carrying member.

7. In a railway car truck of the type having a side frame provided with a bolster opening having a tension member at the bottom thereof, a bolster having an end portion extending into the opening and springs for supporting the bolster by the side frame, the improvements which comprise coil springs supported by the top of said tension member and on which the end of the bolster rests, a leaf spring having substantially horizontally disposed superposed leaves, arranged within the bolster and extending lengthwise thereof, the bolster resting on the end portions of the leaf spring, and means supported by the side frame and cooperating with the medial portion of the leaf spring whereby the latter forms a main load-carrying member.

8. In a railway car truck of the type having a side frame provided with a bolster opening having a tension member at the bottom thereof, a bolster having an end portion extending into the opening and springs for supporting the bolster by the side frame, the improvements which comprise coil springs supported by the top of said tension member and on which the end of the bolster rests, a leaf spring having substantially horizontally disposed superposed leaves, arranged within the bolster and extending lengthwise thereof, the bolster resting on the end portions of the leaf spring, and means extending upwardly from the top of the tension member and engaging the medial portion of the leaf spring 40 for transferring the load placed on the latter to the side frame member.

9. In a railway car truck of the type having a side frame provided with a bolster opening having a tension member at the bottom thereof, 55 a bolster having an end portion extending into the opening and springs for supporting the bolster by the side frame, the improvements which comprise coil springs supported by the top of said tension member and on which the end 60 of the bolster rests, a leaf spring having substantially horizontally disposed superposed leaves, arranged within the bolster and extending lengthwise thereof, the bolster resting on the end portions of the leaf spring and having an opening 65 in its bottom, and means extending upwardly from the top of the tension member and engaging the medial portion of the leaf spring for transferring the load placed on the latter to the side 70 frame member, the last-mentioned means including a post extending loosely through the opening in the bottom of the bolster and into engagement with the bottom of the leaf spring.

10. In a railway car truck of the type having a side frame provided with a bolster opening 75

- having a tension member at the bottom thereof, a bolster having an end portion extending into the opening and springs for supporting the bolster by the side frame, the improvements which comprise coil springs supported by the top of said tension member and on which the end of the bolster rests, a leaf spring having substantially horizontally disposed superposed leaves, arranged within the bolster and extending lengthwise thereof, the bolster resting on the end portions of the leaf spring, means supported by the side frame and cooperating with the medial portion of the leaf spring whereby the latter forms a main load-carrying member, and a member movably connected to the bolster and forming a bearing for an end portion of the leaf spring to facilitate the introduction of the leaf spring into or removal of the leaf spring from the bolster.
11. In a railway car truck of the type having a side frame provided with a bolster opening having a tension member at the bottom thereof, a bolster having an end portion extending into the opening and springs for supporting the bolster by the side frame, the improvements which comprise coil springs supported by the top of said tension member and on which the end of the bolster rests, a leaf spring having substantially horizontally disposed superposed leaves, arranged within the bolster and extending lengthwise thereof, the bolster resting on the end portions of the leaf spring, means supported by the side frame and cooperating with the medial portion of the leaf spring whereby the latter forms a main load-carrying member, and a removable spring block arranged at one end of the bolster and bearing against the top of the bolster and also against one end portion of the leaf spring, said block retaining the leaf spring when in place and permitting its introduction or removal when the block is removed.
12. In a railway car truck of the type having a side frame provided with a bolster opening having a tension member at the bottom thereof, a bolster having an end portion extending into the opening and springs for supporting the bolster by the side frame, the improvements which comprise coil springs supported by the top of said tension member and on which the end of the bolster rests, a leaf spring having substantially horizontally disposed superposed leaves, arranged within the bolster and extending lengthwise thereof, the bolster resting on the end portions of the leaf spring, means supported by the side frame and cooperating with the medial portion of the leaf spring whereby the latter forms a main load-carrying member, and a removable spring block arranged at one end of the bolster and bearing against one end portion of the leaf spring, said block retaining the leaf spring when in place and permitting its introduction or removal when the block is removed.
13. In a railway car truck of the type having a side frame provided with a bolster opening having a tension member at the bottom thereof, a bolster having an end portion extending into the opening and springs for supporting the bolster by the side frame, the improvements which comprise coil springs supported by the top of said tension member and on which the end of the bolster rests, a leaf spring having substantially horizontally disposed superposed leaves, arranged within the bolster and extending lengthwise thereof, the bolster resting on the end portions of the leaf spring, means supported by the side frame and cooperating with the medial portion of the leaf spring whereby the latter forms a main load-carrying member, the bolster being provided with internal substantially arc-shaped load-carrying seats bearing against the ends of the leaf spring, one of said seats being removable from the bolster to facilitate the introduction of the leaf spring into or its removal from the bolster.
